LEATHER FORMING MACHINE

John T. Riddell, Chicago, Ill.

Application December 18, 1933, Serial No. 702,918

3 Claims. (Cl. 69—1)

This invention relates to the arts of stretching and forming leather, and has particular reference to the formation of spheroidal segments of leather intended for assembly to form footballs, basket balls, volley balls, and the like.

The main objects of this invention are to provide an improved form of machine for stretching leather on a convex form; to provide a machine of this kind whereby the amount of stretching can be accurately gauged and whereby the leather will be subjected in its preliminary stretching to substantially uniform pull in all directions radiating from a common center; and to provide apparatus of this kind which is especially adapted for rapid operation such as is consistent with modern mass production manufacturing operations.

A specific embodiment of this invention is illustrated in the accompanying drawings in which:

Figure 1 is a side elevation, with parts of the frame in section, of a leather stretching machine constructed according to this invention and especially designed for forming leather ball segments of spheroidal shape. For the sake of clearness and simplification of the drawing, some of the stretcher clamps and their associated assemblies are also omitted.

Fig. 2 is a longitudinal sectional detail of one of the stretcher members.

Fig. 3 is a plan view of the machine on a small scale illustrating the radial arrangement of the stretcher members.

Fig. 4 is a sectional detail showing the relation of the form block to its supporting cross head.

Fig. 5 is a detail illustrating a form of ball section such as is formed in the machine illustrated.

Fig. 6 is a sectional detail illustrating the purpose of the groove in the block to accommodate the central seam of the ball section.

Fig. 7 is a perspective view of the type of ball that is made by assembling sections such as illustrated in Figure 5.

The machine shown in the drawings is particularly designed for mass production of pre-formed leather segments which are to be assembled in the manufacture of footballs, basket balls, volley balls and the like, where it is desirable that the finished ball shall accurately conform to a predetermined spherical, spheroidal or oval shape and which segments should be uniformly treated in the process of manufacture so that the finished balls will remain true to form throughout a long period of usage.

In the form shown, the machine comprises a frame 1 having a table-like bed 2 over the middle of which there is mounted a support or cross head 3 having an upstanding centering pin 4, and providing a seat for a form block 5 over which the leather ball sections 6 are to be stretched.

Arranged in a circle or ring about the support 3 is a series of stretcher members which are individually swingable in radial planes with respect to the center of the support 3. Each of the stretcher members in the form shown consists of a clamp 7, a spring balance element 8, and a turnbuckle 9, and is hinged to the table 2.

The support 3 is carried by a pair of vertically-disposed rods 10 which are slidably mounted in suitable bearings in the bed 2 and are connected at their lower ends with a crosshead or nut 11 which is internally threaded to fit the jack shaft 12 which is journaled at 13 in the bed 2 and in a cross frame 14 in the lower part of the frame 1. The shaft 12 has an anti-friction thrust bearing 15 on top of the cross bar 14 and is driven by handwheel 16 acting through beveled gears 17.

In order to provide for gripping leathers of various thickness, each of the clamps 7 has a fixed jaw 18 and a pivoted cam-shaped serrated jaw 19 operated by a lever 20. Each clamp 7 is provided with a clevis 21 at its lower end for pivotal connection with a threaded stem 22 which in turn is connected by the turnbuckle with a threaded stem 23 connected with the plunger 24 of the spring balance element 8. The plunger 24 has a head 25 at its lower end with an indicator 26 extending through a slot in the shell 27 of the spring balance element.

A compression spring 28 bears between the head 25 and the head 29 of the shell 27. The stems 22 and 21 are, of course, threaded right and left respectively. The spring balance element has a clevis connection with a pad 30 bolted to the bed 2. The pads 30 are slotted to receive the bolts 30.1, thus admitting of adjustment to adapt the stretcher elements to various stretcher block contours.

The operation of the device shown is as follows:

The particular conformation of the form block 5 is, of course, determined by the type of ball which is being manufactured. In the form shown in the drawings, the block is designed for making spherical balls of the type illustrated in Figure 7 in which the surface is divided into six main sections of spherically rectangular 55

form and each of these sections is made up of two pieces. These two pieces are cut to suitable form, sewn together so as to roughly approximate the curvature of the mold. The section is then soaked in water to render the leather pliable and laid over the mold block 5 as in Figure 1, the mold block being grooved to accommodate the seam between the two parts. The clamps 7 are then fastened to the margins of the leather sheet at uniformly spaced intervals around its entire perimeter and by means of the turnbuckles 9 the tension on all of the stretcher elements is equalized by bringing the indicators 26 of the spring balance in line with the same respective scale graduation on the shells.

By turning the handwheel 16 the jack is operated to lift the crosshead 3 and form block to a distance determined by watching the scale on one of the spring balances and stopping when the pointer indicates the desired strain to which the leather is to be subjected, this being determined by experience.

The margins of the leather sheet are then secured to the block 5 by a row of tacks indicated at 31. The clamps are then thrown off and the operation is repeated with a new block 5 and a new sheet of leather. The form blocks are preferably made of hard wood such as maple.

The term leather as herein used is intended to include leather compositions and any other sheet material which might be substituted therefor and to the stretching and forming of which the invention is applicable.

Although but one specific embodiment of this invention is herein shown and described, it is to be understood that numerous details of the

structure illustrated may be altered or omitted without departing from the spirit of the invention as defined by the following claims:

I claim:

1. A device of the class described comprising a central support having a seat for a form block, a series of stretcher members arranged in a ring about said support, leather gripping clamps on the ends of said stretcher members, said stretcher members being longitudinally adjustable, spring balance elements interposed in said stretcher members, and jack means acting to shift said support relative to said stretcher members. 5

2. A device of the class described comprising a central support having a seat for a form block, a series of stretcher members arranged in a ring about said support, leather gripping clamps on the ends of said stretcher members, turnbuckles interposed in said stretcher members for longitudinal adjustment thereof, spring balance elements interposed in said stretcher members, and jack means acting to shift said support relative to said stretcher members. 10

3. A device of the class described comprising a support for a sheet of leather, a series of individually adjustable stretcher members positioned and arranged to grip the margin of such sheet of leather, means associated with each of said stretcher members arranged to indicate the amount of tension therein, and means coacting with said stretcher members for simultaneously increasing their pull on the margins of said sheet. 15
